WILLIAM HANDLER, OF JERSEYVILLE, ILLINOIS.

NON-REFILLABLE BOTTLE.

1,266,121.

Specification of Letters Patent.

Patented May 14, 1918.

Application filed September 6, 1917. Serial No. 190,020.

To all whom it may concern:

Be it known that I, WILLIAM HANDLER, a citizen of the United States, residing at Jerseyville, in the county of Jersey and State of Illinois, have invented a new and useful Non-Refillable Bottle, of which the following is a specification

The invention relates to a bottle construction, and more particularly to the class of nonrefillable bottles.

The primary object of the invention is the provision of a bottle of this character wherein the contents thereof can be readily dispensed, and on the emptying of said contents, it is impossible to refill the bottle, thereby eliminating the surreptitious use of the bottle, or the adulteration of the original contents, so that the genuineness of the contents is assured.

Another object of the invention is the provision of a bottle of this character wherein the construction thereof is novel in form, whereby fraudulent adulteration and refilling are positively prevented, and the original contents can be freely decanted.

A further object of the invention is the provision of a bottle of this character, which is comparatively simple in construction, possessing few parts, which are readily and easily assembled, strong, durable, thoroughly reliable and efficient in its purpose, and inexpensive in manufacture.

With these and other objects in view, the invention consists in the features of construction, combination and arrangement of parts, hereinafter fully described, illustrated in the accompanying drawing, and pointed out in the claims hereunto appended, it being understood that various changes in the form, proportion, size and manner of details of construction within the scope of the appended claims may be resorted to, without departing from the spirit of sacrificing any of the advantages of the invention.

In the accompanying drawings:—

Figure 1, is a fragmentary elevation of a bottle partly in vertical longitudinal section, constructed in accordance with the invention.

Fig. 2, is a vertical longitudinal detail sectional view.

Fig. 3, is a fragmentary elevation, partly in section, through the cap of the bottle.

Fig. 4, is a sectional view of the line 4—4 of Fig. 1, looking in the direction of the arrow.

Fig. 5, is a sectional view of the line 5—5 of Fig. 1, looking in the direction of the arrow.

Fig. 6, is a perspective view of a guard disk.

Similar reference characters indicate corresponding parts throughout the several views in the drawing.

Referring to the drawing in detail, A 65 designates a portion of the body of a bottle which may be of any desirable shape, and usually constructed from glass, and B the neck of said bottle, which is preferably of uniform cross sectional area throughout its 70 length, and such length thereof can be varied as the occasion may require.

At the mouth or the free end of the neck B, is a valve cage 10 in which is held a spherical valve 11, which prevents the flow of 75 liquid into the bottle. Formed on the neck externally thereof at the inner portion of the same, is the screw thread 12, while spaced from this thread at intervals circumferentially of the neck are lugs 13, and 80 embracing this point of said neck is a band 14, preferably made from aluminum, having stamped, cut, or otherwise formed therefrom, a series of resilient tongues 15, which are slightly bent outwardly to overlie the 85 lugs 13, and are adapted for ratchet action in a manner, and for the purpose herein-after fully described.

The outer end of the neck B, has fitted therein the reduced end 16, of the valve cage 90 10, the end 16 being formed with a valve seat 17 for the valve 11. Contacting with the cage 10, is a guard disk 18 having a central hole 19, and in opposite sides radially extending grooves or channels 20, which 95 open through the peripheral edge of said disk 18, and into the central hole 19, the latter being in registration with the bore in the reduced end 16 of the valve cage. The guard disk 18 limits the unseating movement of the valve 11. Inclosing the neck B, cage 10 and guard disk 18, is a cap 21, hereinafter fully described.

The cap 21 is formed with an internal thread 22, to coöperate with the external 100 105 thread 12, on the neck B for working of the

cap in place thereon. Spaced inwardly from the threads 22 on the inner face of the cap 21, are formed teeth or ribs 23, with which engage the resilient tongues 15, which ride 5 over the teeth or ribs 23, in ratchet like action on the screwing of the cap 21, upon the neck of the bottle. The tongues 15 when locked with the teeth or ribs 23, secure the cap 21 upon the neck of the bottle to avoid 10 the removal thereof by the unscrewing of the same therefrom. The lugs 12, as shown in Fig. 5, constitute a means to hold the tongues against straightening. Surrounding 15 the neck B, at the point of juncture thereof with the body A, is a cork washer 24, against which rests the cap 12, when secured to the neck, and in this manner a fluid tight joint is had between the cap and neck of the bottle.

20 The cap 21 is formed in its outer end with a central discharge opening 25, into which lead the lateral radially extending passages 26, formed in a boss 27, which is of less diameter than the internal diameter of the 25 cap 21, and projects into the latter to engage with the guard disk 18, to hold the same in place, the passages 26, in the boss 27, being designed to deliver the liquid to the discharge opening 25, for the dispensing of the 30 liquid from the body A of the bottle on the unseating of the valve 11, on the tilting of the bottle from upright position.

The boss 27, constructed in a manner hereinbefore stated, prevents the insertion of an 35 instrument through the discharge opening 25, in the cap for the purpose of unseating the valve, or for the detachment of the cap 21, from the neck B, of the bottle to enable 40 the surreptitious refilling of the bottle or fraudulent alteration of its original contents.

The contents of the bottle can be freely 45 decanted, and originality or genuineness of such contents is assured, because on the dispensing or emptying of the contents, the bottle can not be refilled, nor is it possible to adulterate the original contents.

The guard disk 18, is of less diameter than the internal diameter of the cap. The channels or grooves 20 in the guard disk 18, permit the free flow of liquid from the body 50 A of the bottle, through the neck B, and in the event that the valve 11 is seated in said neck and an attempt is made to fill the bottle, the liquid introduced will flow through 55 the grooves or channels 20, in said guard about the cage 10, into the vacant space within the cap 21, thereby filling said space, and thus preventing the inflowing of the 60 liquid through the neck B into the body of the bottle. The weight of the liquid against the valve 11 will positively hold it seated, and thereby shut off any communication with the interior of the body of the bottle.

65 From the foregoing it is thought that the

construction and manner of operation of the bottle will be clearly understood, and, therefore, a more extended explanation has been omitted.

What is claimed is:

1. In a non-refillable bottle, the combination of a container having a neck, a cap fitted on and engaging the exterior of the neck and having a top discharge opening, a boss at the inner end of the discharge opening formed integral with the outer end of the cap, a valve cage supported by the neck and of smaller diameter than the cap so as to be spaced therefrom, a valve within the cage, and a guard supported upon the valve cage and interposed between said cage and the boss, said guard being separate from both the cage and the boss and having a central opening and passages leading therefrom to the periphery, the boss being closed at its center and communicating at its periphery with the space between it and the cap.

2. In a non-refillable bottle, the combination of a container having a neck, a cap fitted on and engaging the exterior of the neck and having a top discharge opening, a boss integral with the cap and located at the inner end of the discharge opening, and considerably greater in diameter than said opening but of less diameter than the cap, said boss having radial passages for the flow of liquid from the periphery of the boss to the center thereof and then out through the discharge opening, a valve cage having a reduced end fitted within the neck and supported on the outer end of the latter and also smaller in diameter than the cap, said cage having its outer end open, a valve for the cage, and a guard for the valve smaller in diameter than the cap and mounted on the outer open end of the cage and interposed between the cage and the boss and bearing against both parts, said guard limiting the unseating movement of the valve and having a central opening with passages leading therefrom to the periphery of the guard.

3. In a non-refillable bottle, the combination with a container having a neck, a cap fitted on and engaging the exterior of the neck and having a top discharge opening, an integral boss at the inner end of the discharge opening for covering the same, said boss having passages leading from the outer edge of the boss to a point in line with the discharge opening for the flow of liquid through the latter, a valve cage supported upon the outer end of the neck, a valve for said cage, and a guard separate from the cage and boss and supported by the cage to limit the unseating movement of the valve, said guard having a central opening and passages leading therefrom to the periphery of the guard, and said guard bearing against the boss, both the guard and

the boss being of a diameter less than the internal diameter of the cap so as to leave spaces between the cap and the peripheries of the guard and boss, which allow communication in a tortuous manner from the interior of the cage to the top discharge opening.

4. In a non-refillable bottle, the combination with a container having a neck, of a cap fitted to the neck, a band fixedly surrounding the neck and having resilient locking tongues, internal locking ribs on the cap and engaged by the tongues, movable means within the cap for preventing the introduction of liquid within the container, and lugs on the neck to coact with the tongues so as to hold the same against straightening.

5. In a non-refillable bottle, the combination with a container having a neck, of a cap fitted to the neck, a band fixedly surrounding the neck and having resilient locking tongues, internal locking ribs on the cap and engaged by the tongues, movable means within the cap for preventing the introduction of liquid within the container, and means on the neck to coact with the tongues to hold the same against straightening.

6. In a non-refillable bottle, the combination with a container having a neck, of a cap threaded on the neck, a band fixedly surrounding the neck above the threaded connection and having resilient locking tongues, internal locking ribs on the cap and engaged by said tongues, and movable means

within the cap for preventing the introduction of liquid within the container.

7. In a non-refillable bottle, the combination with a container having a neck, of a cap threaded on the neck, a band fixedly surrounding the neck above the threaded connection, and having resilient locking tongues, internal locking ribs on the cap engaged by the tongues, movable means within the cap for preventing the introduction of liquid within the container, and means on the neck to coact with the tongues to hold the same against straightening.

8. In a non-refillable bottle, the combination with a container having a neck, of a cap provided with a hole threaded on the neck, a band fixedly surrounding the neck above the threaded connection and having resilient locking tongues, internal locking ribs on the cap engaged by the tongues, movable means within the cap for preventing the introduction of liquid within the container, a washer surrounding the base of the neck and engaged by the cap, and lugs on the neck to coact with the tongues to hold the same against straightening.

In testimony that I claim the foregoing as my own I have hereto affixed my signature in the presence of two witnesses.

WILLIAM HANDLER.
